UNITED STATES PATENT OFFICE.

CHRISTIAN NIELSEN, OF MIDDLETOWN, CONNECTICUT.

COMBINATION-TOOL.

No. 832,996.

Specification of Letters Patent.

Patented Oct. 9, 1906.

Application filed June 6, 1906. Serial No. 320,424.

To all whom it may concern:

Be it known that I, CHRISTIAN NIELSEN, a subject of the King of Denmark, and a resident of Middletown, in the county of Middlesex and State of Connecticut, have invented a new and Improved Combination-Tool, of which the following is a full, clear, and exact description.

The purpose of the invention is to provide 10 a tool especially adapted for use by machinists, but which is also of value to all mechanics, and which may be used as a scribe, a carpenter's square, a compass, gage, &c., and to so construct the tool that it will be simple, 15 compact, durable, and economic, and convenient of arrangement and manipulation.

The invention consists in the novel construction and combination of the several parts, as will be hereinafter fully set forth, 20 and pointed out in the claims.

Reference is to be had to the accompanying drawings, forming a part of this specification, in which similar characters of reference indicate corresponding parts in all the 25 figures.

Figure 1 is a perspective view of a tool arranged for use as a scribe, square, compass, and gage. Fig. 2 is a sectional plan view of the tool when arranged as shown in Fig. 1. 30 Fig. 3 is a transverse section taken practically on the line 3 3 of Fig. 1. Fig. 4 is a transverse section taken substantially on the line 4 4 of Fig. 1. Figs. 5 and 6 are perspective views of other adaptations of the tool, 35 and Fig. 7 is a perspective view of a support for the scribe and which constitutes a portion of the tool when the arrangement is that shown in Fig. 6.

The body A of the tool is in the form of a 40 bar having a flat upper and lower face and a flat side face 10 and an opposing concaved or dished side face 11, as is best shown in Fig. 2. The said body-bar A is also provided at what may be termed its "rear" end portion with 45 a longitudinal slot 12, extending through from top to bottom and parallel with its flat or plain side 10. The upper end of an arm 13 is passed through the slot 12, and said portion of the arm 13 is provided with a longitudinal slot 14, through which slot a set-screw 50 15 is passed, which set-screw likewise passes through the outer end portion of the body-bar A. Thus the arm 13 may be adjusted at any desired angle relatively to the body-bar 55 A and can be likewise adjusted vertically and

held in vertical position by the said set-screw 15. The lower end of the arm 13 is more or less concaved, so as to provide a point 14^a at what may be termed the "lower" portion of its forward edge, as shown in Figs. 1 and 5, 60 and this point 14^a when used in connection with a scribing-bar 16 will serve the purpose of a compass or calipers. The scribe-bar 16 is passed down through an opening 17 in the body-bar A and is adjustably held by a set-screw 16^a. The said scribe-bar 16 is provided with a head 18, having one end 19 pointed for scribing purposes, and its other end is slotted, so that it can be placed in guided relation to the blade 20, having a 70 scale of inches thereon, which blade extends up from the upper face of the body-bar A at its forward end, as is shown in Figs. 1 and 5. This scaled blade 20, in connection with the body-bar A, forms a carpenter's square and 75 can be used in connection with the scribe 16 and the arm 13, as is shown in Fig. 5.

In connection with the elements which have just been described I employ an auxiliary horizontal scale-arm B, which is in two 80 integral or connected sections—namely, a wide section 21 and a narrow section 23. At the junction of the two sections 21 and 23 the horizontal scale-arm B is attached to the forward end of the body-bar A by means of a 85 screw 22 or its equivalent, so that the horizontal scale-arm B can be readily removed from engagement with the body-bar A, as is shown in Fig. 5, and differently employed, as shown in Fig. 6, to provide for every emergency.

The reduced section 23 of the horizontal scale-arm B is provided with stop-pins 23^a at its outer or free end, and on this reduced section 23 of the aforesaid horizontal scale-arm 95 B a block 24 is mounted to slide, having points or spurs 25 formed at its side faces, the points or spurs being in transverse alignment, as is particularly shown in Fig. 3, so that the said block 24 may be utilized also 100 for scribing purposes or as a gage when required. The said block 24 is held in adjusted position on the horizontal scale-arm B by a set-screw 26 or the equivalent thereof.

A second gage-block 27 is mounted to slide 105 on the wider section 21 of the horizontal scale-arm B, and this latter gage-block 27 is provided with a central section 28, (shown best in Fig. 4,) which extends loosely through a horizontal slot 29 in the said scale-arm sec- 110

tion 21, so that said gage-block 27 has two operating-faces, one at each side of said scale-arm B.

The block 27 is placed in position on the arm-section 21 before a closing-strip 30 is attached to the outer or free end portion of the said scale-arm section 21, as is shown in Figs. 1 and 2. The inner section of the gage-block 27 is provided with upper and lower spurs 31, which may be used for scribing or which may be used as bearing-points, according to the work in hand, and the outer member or section of the gage-block 27, as shown best in Fig. 1, is provided with inclined faces 33 and 34, the bevels of which faces are different, so as to accommodate said portion of the gage-block to surfaces which are inclined or beveled, and the gage-block 27 is held in position on the scale-arm B by means of a suitable set-screw 32, having bearing against a solid portion of the said scale-arm, as shown in Fig. 4. This gage-block 27 is operated through the medium of a screw 35, located in the slot 29 in the wider section 21 of the gage-arm B, and the said screw is provided at its outer end with a suitable milled head 36, whereby to turn the same. When the said scale-arm B is attached to the body-bar A, the inner end of the screw 35 turns in a lug 37, forming a portion of the forward end of the body-bar A.

When certain measurements are required or certain work is to be scribed or gaged, the scale-arm B is disconnected from the body-bar A, as is shown in Fig. 6, and is used in connection with a face-block 37^a, which is provided with an opening 38, extending through from top to bottom for the passage of the body 16 of the scribe, and the said face-block 37^a is provided with a threaded aperture 41 in its outer face to receive the screw 22, passed through the horizontal gage-arm B, and with lug 39, which extends through the slot 29 in the scale-arm B and receives the inner end of the adjusting-screw 35, which adjusting-screw is passed through a suitably-threaded opening in the gage-block 27. Thus it will be observed that when the face-block 37^a is employed the lug 39 takes the place of the lug 37, formed on the body-bar A.

This tool fulfils the purpose of a number of independent tools and occupies but little space in the tool-chest. In fact, it can be readily carried in the pocket, if so desired. It is simple in construction and capable of many adjustments and is well adapted for the purposes intended.

Having thus described my invention, I claim as new and desire to secure by Letters Patent—

1. A tool consisting of a slotted body-bar having a fixed scaled blade at one end at right angles thereto, a scribe-bar passed through the body-bar, and an arm adjustable

in the body-bar, extending parallel with the scribe-bar and in an opposite direction to that of the scaled blade with reference to the body-bar.

2. A tool consisting of a slotted body-bar, a fixed scaled blade at one end of the said body-bar at right angles thereto, a scribe-bar passed through and adjustably held in the body-bar, an arm adjustable in the said body-bar, extending therefrom in a direction opposite to that of the scaled blade and parallel with the scribe-bar, said adjustable arm having a pointed lower end, and the said scribe-bar being provided with a head-section pointed at one end and having removable connection with the scaled blade at its opposite end.

3. In a tool, the combination with a body-bar, a fixed scaled blade secured to one end of the body-bar and extending at right angles thereto, a scribe-bar passed through and adjustably secured to the body-bar, and an arm adjustable in the slotted portion of the body-bar, extending therefrom in a reverse direction to the direction of the said blade but parallel with the scribe-bar, the said arm having a pointed lower end, of a horizontal scaled arm secured to the end of the body-bar at which the scaled blade is located, independent gage-blocks mounted to slide upon the said horizontal scaled arm, and means for holding the said gage-blocks in position on the said horizontal arm.

4. In a tool, the combination with a body-bar, a fixed scaled blade secured to one end of the body-bar and extending at right angles thereto, a scribe-bar passed through and adjustably secured to the body-bar, and an arm adjustable in the slotted portion of the body-bar, extending therefrom in a reverse direction to the direction of the said blade but parallel with the scribe-bar, said arm having a pointed lower end, of a horizontal scaled arm secured to the end of the body-bar, the said scaled arm being in two sections, one wider than the other, a gage-block held to slide on the narrower section of the said arm, having spurs extending from opposite sides, a screw-shaft mounted to turn in the wider section of the said horizontal arm, and a second gage-block engaging with both sides of the wider section of said horizontal arm, which gage-block is operated by the said screw, the said latter gage-block having spurs extending from one side member, the opposite side member having inclined faces, and means for securing the two blocks independently in adjusted position.

5. A tool consisting of a support, a scribe-bar adjustably held in said support and extending through the same, a horizontal scaled arm secured to the said support, the said horizontal arm being in two sections, a wide and a narrow section, a gage-block mounted to slide on the narrow section of said arm, a

screw mounted to turn in the wider section of said arm, and a second gage-block operated by the said screw and engaging with opposite faces of said wider section of the arm, 5 one outer face of the latter gage-block being provided with spurs and the opposing outer portion of said gage-block having its upper end beveled.

In testimony whereof I have signed my name to this specification in the presence of 10 two subscribing witnesses.
